UNITED STATES PATENT OFFICE.

HENRY M. PRIEST, OF ELMIRA, NEW YORK, AND ROBERT H. FORD, ALEXANDER L. GREENABAUM, AND CHARLES P. RICHARDSON, OF CHICAGO, ILLINOIS, ASSIGNEES TO SAID CHARLES P. RICHARDSON, TRUSTEE.

CONCRETE BUILDING CONSTRUCTION.

Application filed October 7, 1920. Serial No. 415,322.

Our invention relates to a building construction composed of reenforced, pre-cast units of concrete; the units being all of such formation or nature as to be portable and constructed so that they may be readily set up in co-operative relation or association, to provide the walls and partitions of a building, with the respective elements or units so formed that they may be firmly secured together or locked in place to provide a weather-proof and rigid construction.

Our invention is particularly adapted to provide the various units for forming the main side or outer walls and the partitions or inner walls of a building and more especially a building wherein the walls are so arranged as to provide air spaces or chambers intermediate of both sides of the walls; the respective units being formed that they may be readily assembled and put into place, and at the same time quickly "knocked down" and arranged in convenient and compact form for transportation.

The invention and its advantages will be more readily comprehended from the following detailed description of the drawings, wherein:

Figure 1 is a side elevation of a garage type of building constructed from our unit parts and illustrating a door opening.

Figure 2 is a detail sectional view taken on the line 17, 17 of Figure 1, looking in the direction of the arrows.

Figure 3 is a detail view in perspective of the upper portion of the outer corner or door post employed in Figure 1.

Figure 4 is a similar view of what may be termed the inner door post, namely the post intermediate of the corners of the building as illustrated in Figure 1.

Our invention is more especially adapted for single story buildings, cottages, garages and the like; and in the exemplification disclosed in Figure 1 where a building is shown formed of our pre-cast units, it comprises a concrete corner post 30, of length commensurate with the height of the building intended to be constructed. The post 30 is previously cast or molded with suitable reenforcing elements or rods disposed lengthwise thereof, and for the sake of lightness is preferably provided with a central opening 32 to provide a hollow column or post, which, however, will be of ample

strength. The post is angular in cross section and formed to provide portions disposed parallel with two of the outer sides of the post adapted to overlap the adjacent wall members as shown at 33 in Figure 3, and thus also provide abutting surfaces for the outer wall-forming slabs or panels 34, whereby the latter are maintained in place. The wall is preferably of double wall construction; and the inner and outer panels 34 may be identical in construction and arranged in superposed relation. The longitudinal sides of the post, adapted to be disposed intermediate of the inner and outer wall panels, may be provided with angularly formed holes, or somewhat T-shape bolt-receiving openings, as disclosed at 38 in Figure 3, wherein the upper end is made sufficiently large to receive the head of a suitable bolt while the lower end of the slot or socket is restricted to prevent withdrawal of the bolt-head. The openings or slots in the sides of the posts are preferably provided with metallic inserts, of formation corresponding with the description of openings heretofore given.

The invention contemplates the use of suitable posts or uprights disposed intermediate of the ends of adjacent slabs or panels, thus providing the building with posts or uprights placed at equi-distances apart, as illustrated at 43 in Figure 1. The intermediate posts 43 are also of pre-cast concrete construction with suitable reenforcing elements, and these posts may also be made hollow, if desired, except for the upper ends; the upper ends of all posts being preferably solid to provide a bolt-head receiving socket. The intermediate posts 43 preferably have one of the sides provided with integral and laterally disposed extensions or wings, the extensions being disposed in opposite directions parallel with the outer longitudinal side of the post so as to provide integral battens adapted to overlap the adjacent ends of the outer wall panels 34. With the construction illustrated in Figures 1 and 2, it is apparent that none of the posts have bolt-receiving openings on their outer sides, with the result that the outside of the building is given a smooth, neat appearance and finish.

In order to properly secure the ends of the posts in place and to provide them with

cross members or wall plates, as at 49, the ends of the posts are also preferably provided with the T-shape sockets 38, and where hollow posts are employed the ends 5 are preferably cast solid and provided with T-shaped sockets, adapted to receive the heads of the bolts for securing the cross members or wall plates in place and therefore also to maintain the posts in spaced relation as well as providing means whereby 10 the roof timbers are supported and secured in place. The roof may be of any well known construction; or the rafters may also be of reinforced concrete and bolted to the 15 wall plate or member 49; while the upper part of the wall beneath the eaves may be finished with a suitable frieze board, as shown at 50 in Figure 2. In order to provide a finished effect and permit the frieze 20 board to come flush with the outer wall panels, the battens or wings, formed integral with the outside posts, preferably terminate a distance from the upper ends of the posts commensurate with the width of 25 the frieze-board, while Figure 3 illustrates the manner of forming the corner extension 33; the bottom edge of the frieze-board and the upper ends of the integral battens or wings are oppositely beveled to permit an 30 interlocking and weather-proof relation between the frieze-board and the battens or extension of the posts.

In Figure 1 we illustrate a small building or garage provided with a hip roof and with 35 a door opening which is provided with a lintel 61 of reinforced concrete kerfed or rabbeted along both upper longitudinal edges as shown at 62 in Figure 2. By kerfing the longitudinal edges of the lintel 61 as just 40 described, the latter is provided with the central and upwardly disposed portion 63 which will constitute a spacing portion for the inner and outer slabs or panels 64. This 45 space above the lintel is also provided with a short post 65 similar in construction to the post 43 shown in Figure 1, provided with bolt-head receiving sockets as previously described and with the wings or batten portions 50 thereof terminating a distance from the upper end of the post and beveled as shown in Figure 2, to receive the lower beveled edge of the frieze-board 50. The outer corner post 66 is substantially similar 55 to corner post 30, except that the upper end is constructed as shown in Figure 3, where the upper end on the side adapted to receive the end of the lintel 61 is provided with a channel or groove 67 formed to receive a centrally extended portion of the end of the 60 lintel 61, as shown in Figure 4, where the upper end of the inner door post 68 is shown in detail. The lintel 61 is adapted to rest on the abutment or shoulder shown 65 at 69 in Figure 3, with its extended intermediate portion disposed in the groove 67,

while the outer longitudinal side of the lintel is overlapped by the wing or extension 33, which also terminates a distance slightly removed from the upper end of the post and is beveled to receive the lower beveled edge 70 of the frieze-board; the space intermediate of the wing 33 and the groove 67 corresponding with the thickness of the outer wall panels which are arranged in the longitudinally kerfed portion of the lintel 61. 75 The inner door post 68 has its longitudinal side provided with a groove 70, similar to groove 67 in post 66, to receive the end of the lintel 61 and be overlapped on the outer side by the wing or batten portion 71 formed 80 integral with the post. The wing or batten 71 terminates a distance removed from the upper end of the post and is beveled to receive the lower beveled edge of the frieze-board. 85

In the erection of a building, constructed of our improved units, the respective posts are first placed in proper upright position at predetermined distances apart commensurate with the length of the wall panels; 90 the upper ends of the posts being secured together and maintained in proper spaced relation by the cross member 49, after which the outer wall panels may be placed intermediate of adjacent posts and arranged in 95 abutting relation with the integral extensions or batten portions on the outer longitudinal sides of the posts; the wall panels being maintained in position by the spacing elements. At places where the building is 100 to be provided with a door opening, it will be understood, of course, that the lintel 61 is put into place before the wall panels above the lintel are arranged intermediate of the adjacent posts; and after the upper panels have been properly inserted, the frieze-board is then secured in place and in interlocking 105 relation with the beveled extensions of the posts.

We prefer to have all the posts of uniform 110 length to provide a standard height of building, but it will be understood, of course, that where the construction is to differ, so far as the roof is concerned, that some of the posts may vary in length although their general construction will be similar to the posts described, which may be either hollow or solid throughout. 115

We have shown and described what we believe to be the best embodiments of our 120 invention, but modifications may be made in certain details of construction without, however, departing from the spirit of the invention.

What we do claim as our invention and 125 desire to secure by Letters Patent is:

1. In a concrete building construction of precast reinforced concrete units, hollow posts adapted to constitute corner, intermediate and door posts, the exterior side of all 130

of said posts being laterally extended beyond the normal longitudinal edges thereof, the upper ends of the exterior sides provided with said extensions being cut away a predetermined distance and beveled downwardly toward the posts, the ends and inner sides of the posts being provided with bolt-head holding sockets.

2. In a concrete building construction, of precast concrete units, a post of reenforced concrete, the outer side whereof is provided with an integral laterally disposed longitudinal extension, one of the sides of the post at the upper end thereof being provided with a longitudinal recess, the side of the post at a point intermediate of said recess and adjacent sides being formed with panel receiving portions.

3. In a concrete building construction, having concrete lintels with extended end portions and a concrete frieze-board with a lower beveled edge, door-posts whose exterior sides are provided with integral lateral extensions along the longitudinal edges with the upper ends of the extensions terminating short of the ends of the posts to form recesses to receive the frieze-board, while the upper opposing sides of the posts are formed with corresponding channels extending lengthwise to receive the extended end portions of the lintels.

HENRY M. PRIEST.
